(57) CLAIM

The ornamental design for footwear, as shown and described.

DESCRIPTION

FIG. 1 is a top, front, left-side perspective view of footwear showing the new design;

FIG. 2 is a top, back, right-side perspective view thereof;

FIG. 3 is a bottom, back, right-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the footwear that form no part of the claimed design. The dot-dash lines represent a boundary of the claimed design and form not part of the claimed design.

The claimed design includes the mirror images of the embodiment depicted that is not shown.

1 Claim, 9 Drawing Sheets
